UNITED STATES PATENT OFFICE.

LOUIS B. OLIN, OF CHICAGO, ILLINOIS.

REFRIGERATOR VEHICLE.

Application filed May 16, 1921. Serial No. 469,757.

To all whom it may concern:

Be it known that I, LOUIS B. OLIN, a citizen of the United States, and a resident of Chicago, in the county of Cook and State of Illinois, have invented certain new and useful Improvements in Refrigerator Vehicles, of which the following is a specification.

The invention relates to vehicles, and particularly to an improved refrigerator truck 10 for use in distributing and delivering ice-cream and the ingredients for a cooling mixture, such as ice and salt.

I have shown and described a refrigerator truck which embodies some of the features 15 shown and described in my pending application for United States Letters Patent, Serial Number 403,440, filed August 13, 1920.

One of the objects of the invention is the production of a refrigerator truck which 20 will serve to assist in maintaining the proper temperature of the ice-cream with a minimum ice consumption; another object is to provide a construction and arrangement of parts which will eliminate the necessity of 25 frequent ice replenishment in the refrigerator section of the vehicle, thereby effecting a saving in labor and elements going to make the cooling mixture, to wit: ice and salt.

The invention has as a further object the 30 provision of a number of receptacles which are designed to receive the cooling medium, or refrigerant, and which are arranged to surround the cooling chamber produced by the aid of the receptacles. The cooling 35 chamber contains compartments. These receptacles are constructed so that the ice and salt mixture with which they are filled, and which produce the cooling medium, cannot possibly reach the ice-cream, or other com-

modity which is being cooled. In the arrangement produced by the invention, the cans and packages containing the ice-cream do not come in contact with the ice, salt, or other cooling mixture, but are cooled in the 45 compartments which are entirely free of ice and salt. This is of great importance in view of the fact that the ice used is frequently obtained from surrounding lakes and rivers and contains foreign matter which

50 would injuriously affect the ice-cream in the event that it were to come in contact with the cream. This, of course, would render the ice-cream insanitary, unusable and unsalable. It is one of the prime objects of the, 55 invention that the cans and packages containing the ice-cream shall be cooled, but

shall not come in contact with the cooling mixture.

In connection with the refrigerator section of the vehicle, it is an object of the invention to provide storage places for various flavors of ice-cream and for various sizes of containers of the ice-cream, these containers usually being metal cans or paper packages. In the vehicle shown, compartments for the 60 storage of small packages of ice-cream, familiarly known as brick ice-cream, are provided in the lower part of the refrigerator section. Larger compartments are provided in the intermediate part and a single compartment is provided in the upper part for the "bulk" ice cream, which is usually packed in metallic cans.

Another feature of the invention, and one which particularly distinguishes it from the pending application referred to, is the provision of a construction which permits the cooling mixture, or the refrigerant containing receptacles, to be disassembled for the purpose of removing them from the vehicle 70 for repair or other purposes should this be found necessary.

The invention has, for a further object, the provision of an arrangement whereby the ice-cream may be readily accessible without permitting the introduction of relatively warmer air to all of the compartments when one of the compartments is opened to remove or fill the same.

Another of the objects of the invention is 80 to provide a construction and arrangement whereby ice and salt and also ice-cream are readily accessible from the ground without necessitating climbing on and off the vehicle.

The invention has for a further object the provision of a refrigerator truck, the walls of which are constructed and so insulated as to maintain a temperature in the various compartments of the refrigerator section, 100 which will keep the ice-cream, or other commodity confined therein, in its proper condition.

The vehicle is also constructed so that it may accommodate and carry the empty ice-cream cans and covers therefor, preventing their loss and hiding them from view, thus improving the appearance of the vehicle.

The vehicle is further constructed with salt and ice compartments adapted to carry 110 a large quantity of salt and ice to be supplied to the customers for use in their re-

frigerators in which ice-cream to be sold by them is stored and kept in a salable condition. The salt container is provided with means for readily filling it from either the 5 top or the side and the container is also provided with an arrangement whereby the salt may be readily removed from the container when this is desired. The ice container, or enclosure, herein before referred to is arranged adjacent the salt container. A means 10 is provided therein for preventing the water produced by the melting ice in this enclosure from reaching the salt.

A modified arrangement embodying the 15 invention is shown and described in which the cooling chamber in the refrigerator section of the truck is divided by a cooling mixture receptacle placed transversely to the other cooling mixture receptacles. This arrangement provides for cooling compartments on both sides of the refrigerator section with a cooling mixture receptacle between, and also provides for means of entry 20 to the compartments on both sides of the refrigerator section. In this arrangement, the drawers in the lower cooling compartments into which ice-cream in brick form is stored are shorter and therefore they may be moved into and out of their respective compartments 25 in their respective cooling chambers more readily than the long drawers shown and referred to in the remaining drawings and description. This modified form of refrigerator truck is particularly useful in 30 operating in crowded city streets where space is limited.

The invention will be described in detail and more readily understood when read in conjunction with the accompanying drawings 40 illustrating the invention together with the modified form which has been referred to. It will be obvious that other changes and modifications may be employed without departing from the spirit of the appended 45 claims forming a part hereof.

In the drawings,

Figure 1 is a side elevation having the invention applied thereto;

Figure 2 is a central longitudinal section 50 of the invention shown in Figure 1 drawn to a larger scale;

Figure 3 is a horizontal section taken on line 3—3 of Figure 2 looking in the direction of the arrows;

55 Figure 4 is a transverse section taken on line 4—4 of Figure 2;

Figure 5 is a sectional view of a curtain construction employed to hide the empty cans from view;

60 Figure 6 is a section taken on line 6—6 of Figure 5;

Figure 7 is a fragmentary detail of the structure shown in Figure 5;

65 Figure 8 is a partial horizontal section of the refrigerator portion of the structure

embodying the invention showing a modified arrangement which may be employed;

Figures 9, 10 and 11 are details of portions of the structure shown in Figure 8; and

Figure 12 is a plan view of the upper mixture receptacle. 70

In the embodiment of the invention illustrated in the drawings, the vehicle is provided with a box, or body 13 having walls which are suitably constructed for a vehicle 75 refrigerator and which include suitable insulating material. The body is mounted upon cross-beams 14, which are in turn arranged upon the chassis 15 of the truck which carries the entire structure. The 80 truck is provided with the usual driver's seat 16 and the canopy 17. At the rear end of the vehicle there is provided a compartment 18 within which may be stored the empty cans which are gathered from the 85 customers. Below the body 13 and adjacent the compartment 18 is arranged a compartment 19 for the reception of the caps or covers removed from the cans stored in the compartment 18.

The interior of the body 13 is provided with various enclosures, chambers, compartments and receptacles. In the forward end of the vehicle toward the driver's seat are arranged the enclosures for the ice and 90 salt. Back of these is the refrigerator section of the vehicle which is separated from the ice and salt enclosures by a wall constructed like the main walls, floor, top and body of the vehicle. This refrigerator section contains the enclosure which in turn contains the cooling chamber which is divided into compartments of various sizes for the reception and storage of various sized cans and packages of ice-cream. The 95 cooling chamber, when in normal use, is substantially surrounded by receptacles containing the cooling mixture and in turn these receptacles are substantially surrounded by suitable insulating material. In the 100 embodiment of the invention shown in Figures 1, 2, 3 and 4 the cooling chamber is shown with removable cooling mixture receptacles on three sides and top and with suitably insulated top-wall, floor, doors and 105 side walls. This insures that the ice-cream will be kept in good and salable condition, irrespective of the temperature outside of the vehicle or the distance of the customer's place of business from the central delivery 110 station.

The forward portion of one of the side walls of the body 13 is provided with sliding doors 20, 21 and 22. The top of this forward portion is provided with the closure 115 23. The sliding doors 21 and 22 permit access to the salt container 24 and the sliding door 20 and the closure 23 permit access to the ice compartment or enclosure 25. The salt container has an inlet 26 whereby 120

130

salt may be introduced therein without necessitating the exposure of the ice provided in the enclosure 25. The door 21 may also be utilized for this purpose when desired. The door 22 is arranged at a lower level and permits ready access to the salt so that it may be taken from the container 24 from the outside of the vehicle.

The refrigerator end of the vehicle is 10 provided with swinging doors 27, 28 and 29 which permit access to the compartments of the cooling chamber, which cooling chamber is generally designated 30. This cooling chamber is divided into a plurality of 15 separate compartments 31, 32, 33, 34 and 35. The compartments 31, 32, and 33 may receive and accommodate the cans of cream. The remaining compartments 34 and 35 are of a lesser height and will readily accommodate the sliding drawers 36, 37, 38 and 39. These latter compartments are arranged below the compartments 31, 32 and 33 so that they will readily permit access thereto to insert and remove the bricks of cream while 20 the driver stands on the ground and without requiring him to climb up on the truck. The door 27 closes the compartment 31. The door 28 closes the compartments 32 and 34. The door 29 closes the compartments 33 25 and 35. The doors 28 and 29 also allow access to the drawers 36, 37, 38 and 39. It is therefore apparent that access may be had to the ice-cream, or other commodity contained in one compartment without necessitating the admission of warm air 30 into all the other compartments.

The cooling chamber 30, containing the compartments 31, 32, 33, 34 and 35, is surrounded at three of its sides and at its top 40 by removable or separable metallic receptacles or containers which form the walls of these compartments. These receptacles are adapted to contain the refrigerant, or the cooling medium whereby the ice-cream, 45 or other commodity stored in the compartments may be kept in proper condition. These receptacles at the three sides of the cooling chamber 30 are clearly shown in Figure 3 and are designated by the numerals 40, 41 and 42. These receptacles are 50 adapted to be separated from each other so that one may be separated or removed from the vehicle without necessitating the removal of all of them should this at any 55 time be found necessary or desirable. These receptacles are substantially rectangular in shape and are each provided with a plurality of transverse walls, or partitions 43, which are channel shaped and held with relation to the side walls of these refrigerant 60 receptacles. These transverse partitions 43 divide the receptacles into separate compartments into which the cooling mixture may be placed and packed to cool the cooling chamber 30 and its compartments.

It has been found in actual practice that very good results in refrigeration have been obtained by the employment of these partitions which divide the cooling mixture receptacles which are placed at the sides of 70 the cooling chamber into smaller divisions or compartments. These partitions tend to keep the mixture in compact masses in their respective divisions, or compartments and practically free of independent movement 75 although in normal use the vehicle is subjected to a great amount of vibration and strain.

A drain pipe 44 leads from the bottom of each of these receptacles and extends 80 through the lower floor board 45 of the vehicle. These drain pipes relieve the receptacles of the brine which results from the melting of the mixture.

The transverse partitions 43 of the mixture receptacles do not extend the full length thereof either at the top or the bottom, as shown at 43^a and 43^b in Figures 2 and 4. At the top they provide room for the downwardly projecting flanges 46 of the uppermost mixture receptacle 47. At the bottom the transverse partitions 43 are terminated a sufficient distance above the bottoms of the mixture receptacles 40, 41, and 42 to permit free circulation of brine to the drain pipes 95 44. The mixture receptacle 47 provides the top wall of the cooling chamber 30. The flanges 46 surround three openings 48, 49 and 50 in the bottom of the mixture receptacle 47. These openings communicate with 100 the tops of the receptacles 40, 41 and 42. The flanges 46 substantially conform in outline to the openings and last named receptacles. The flanges 46 also assist in holding the receptacle 47 with respect to the receptacles 40, 41 and 42 from the side walls of the cooling chamber. In addition, the flanges 46 prevent water or brine from finding its way into the cooling chamber 30. The receptacle 47 is substantially rectangular in outline and is provided at its uppermost edge with the circumferential laterally extending flange 51 which rests upon the inner walls 52, 53, 54 and 55 of the refrigerator enclosure of the vehicle which surround the 110 cooling chamber generally designated 30. The uppermost mixture receptacle 47 is provided with angle iron strips 56 and 57 which strengthen the receptacle so that it will maintain and carry the weight of the cooling 115 mixture. The receptacle is secured in place by means of the wood screws 58 which enter the walls 52, 53, 54 and 55. The wall generally designated 59 divides the interior of the vehicle body so as to separate the refrigerator section from the ice and salt enclosures.

The cooling chamber 30 is divided to produce a plurality of compartments and therefore the chamber is provided with horizontal 120

partitions 60 and 61 and vertical partitions 62, 63 and 64. The partitions 60 and 61 are removably secured to the side walls of the compartment 30, or to the inner walls of the mixture receptacles 40, 41 and 42 by being bolted to the angle irons 65 and 66 which are secured to the inner walls of the mixture receptacles 40, 41 and 42. The space interposed between the horizontal partition 61 and the upper floor boards 67, which is the bottom of the cooling chamber 30, is utilized for the accommodation of the drawers 36, 37, 38 and 39. This space is divided by the vertical channel iron partitions 63 and 64 which rest upon the upper floor boards 67 and support the partition 62 at the center line thereof. By reason of the fact that the partition 62 is arranged immediately above the partitions 63 and 64, the whole interior structure of the cooling chamber is supported.

From the foregoing description, it is evident that by unscrewing the wood screws 58 the receptacle 47 may be lifted away from the sub-structure of the cooling chamber 30, and by undoing the bolts and nuts which bind the parts 60 and 61 to the angle iron strips 65 and 66, these partitions may also be lifted away, or removed from between the inner walls of the refrigerant containers 40, 41 and 42. The partitions 62, 63 and 64 may also be disconnected and removed from between the walls of the refrigerant containers. The removal of these partitions allows either one or all of these containers to be removed from the vehicle and replaced in the event that repairs or replacement of the containers becomes necessary. These refrigerant containers 40, 41 and 42 are surrounded by the insulated walls 68, 69, 70 and 59 which include the inner wall portions 52, 53, 54 and 55, the insulating material 71 and the outer wall portions 72, 73, 74 and 75 and the top and bottom floor boards 45 and 67. The wall 70 is provided with the doors 27, 28 and 29 which are also insulated. These walls may be of any desired construction and may include the cross-beams 76, 77 and 78 which close the ends of these walls and prevent any material from finding its way between them.

The uppermost wall of the box or body above the cooling chamber 30 is provided with an opening which is closed by two insulated hinged closures 79 and 80 hinged at 81 and 82 respectively, which are provided to allow the refrigerant receptacles to be filled with the refrigerant. The closures are provided with the handles 83 and 84 whereby they may be readily opened and closed. The edges of these closures engage and rest upon the sides of the opening and are thereby limited in their movement in an inward direction. A strip 85 is provided to seal the juncture of these closures. It is evident that when these closures are opened the cooling

mixture may be packed in the receptacles 40, 41, 42 and 47. If desired these receptacles may be lifted out of the refrigerator section within which they are arranged when the partitions 60, 61 and 62 and other portions 70 of the structure such as the angle iron supports 65 and 66 are detached therefrom.

The outer walls of the box or body may be secured to the remainder of the structure in any suitable manner. That herein shown 75 for securing them in place includes the longitudinally extending parallel beams 86 and 87 arranged adjacent the top of the structure, the sill-beams 88 and 89 arranged at the lowermost part of the box or body and 80 the intermediate beam 90. The sill-beams 88 and 89 rest upon and are supported by the transverse beams 14 which are in turn secured to the parallel under-sills 91 which rest upon the channel beams 92 of the 85 chassis 15.

These transverse beams extend beyond the sides of the box or body to provide a support for the running boards 93 and 94 which are arranged upon the opposite sides 90 of the body and preferably extend from one end to the other thereof. The running board 94 is provided with a hinged extension 95 and provides a wider portion for the driver to stand upon when removing the 95 cans from within the cooling chamber. These last named running boards 94 and 95 may be provided with abutments 96 which abut against each other and assist in maintaining the hinged or swinging board 95 in 100 the position shown in Figure 4.

The rearmost end of the vehicle is, as before stated, provided with a compartment 18 for the accommodation of the empty cans which are gathered from the customers. 105 This compartment is composed of the side walls 97 and 98 and the inclined floor 99. The end of this portion is open excepting it is closed by a curtain 100 which is supported by means of the wires or cords 101 110 and 102 which have their opposite ends respectively connected to the bars 103 and 104. One end of this curtain is secured to one of the bars 103 and the opposite end is free to be raised and lowered upon the wire or 115 cords 101 and 102, which wires or cords are threaded through the openings 105 provided in this curtain 100. When it is desired to place an empty can within the compartment generally designated 18, the curtain 100 may be raised and upon its release it will automatically drop to its lowest position and thereby hide the empty cans contained in the compartment. The curtain and support structure also assist in preventing a loss of cans from the compartment due to jarring and jolting of the vehicle while being driven through the streets.

As before stated, the forward end of the body 13 is provided with a salt contain- 130

ing compartment 24 and the ice compartment 25. The ice used is usually in the form of chips which may be inserted through the opening closed by the closure 5 23 and removed therefrom through the opening closed by the door 20. The walls forming this end of the vehicle body are also insulated so that the ice contained in the compartment 25 will not readily melt 10 while being conveyed through the streets. A metallic pan, having a drain 107 is arranged in the bottom of this compartment and is provided to prevent the water, which naturally would result from the melting of 15 the ice in the compartment 25, from finding its way into the salt container 24. It is of course understood that this pan 106 has an opening which permits of access to the ice through the door 20. The salt container 24, 20 as before stated, is provided with an opening 26 which terminates outside of the uppermost wall of the vehicle body and connects with a chute 108 leading downwardly from the opening into the container 24. A 25 closure 109 is provided for this chute. Thus it can be readily seen that this container can be easily filled from the top through this opening 26 without exposing the ice contained in the compartment 25, or may be 30 filled through the opening which is closed by the sliding door 21. The salt in this container may be removed therefrom through the opening closed by the sliding door 22. This salt compartment 24 may be 35 constructed of the walls 110 and be provided with a metallic roof 111 which is preferably sloped so that it will shed the ice and water as the former is removed from the compartment 25.

40 Figure 8 discloses a modified arrangement of a refrigerator vehicle of which the invention is susceptible. In this construction the opposite sides of the vehicle body are provided with a plurality of openings 45 and closures 112, 113, 114 and 115. This structure embodies the removable receptacles 116, 117 and 118 for the refrigerant. The refrigerant receptacles 116, 117 and 118 are provided with partitions which are constructed similarly to the partitions in the structure hereinbefore described. The container, or receptacle 118 is arranged transversely to the receptacles 116 and 117 and is positioned in this manner to provide cooling 50 chambers on opposite sides thereof. These cooling chambers are again sub-divided to provide a plurality of tiers of compartments to accommodate the cans of ice-cream and also to enclose drawers which extend from 55 the side walls of the body to the transversely arranged refrigerant receptacle 118. It is understood that the vertically arranged refrigerant receptacles in this structure rest upon the floor of the refrigerator section 60 and have their uppermost open ends in

communication with the horizontally arranged refrigerant receptacle 119. This latter receptacle is provided with flanged openings 120, 121 and 122, the flanges of which telescope into the respective refrigerant receptacles 116, 117 and 118. The flanges which fit into the receptacles 116, 117 and 118 are the flanges 123 at the bottom of the refrigerant receptacle 119. This receptacle is also provided at its uppermost 70 edge with the circumferential laterally extending flange 124. This flange rests upon the inner wall boards 125, 126, 127 and 128 of the refrigerant enclosure. The tiers of compartments are produced by the removable vertical partitions 129, and 130 and the horizontal partitions 131, 132, 133 and 134 which are supported in position by means of guide ways 135 secured to the transversely arranged refrigerant container 118 80 and to two of the side walls of the refrigerator section. Angle iron supports 136 are secured, as by rivets 137, to the refrigerant containers 116, 117 and 118 and the removable partitions 129 and 130 to furnish 85 ledges for the placing and securing, as by the bolts and nuts 138, of the horizontal partitions 131, 132, 133 and 134. By resorting to an arrangement such as this cooling chambers are provided upon the opposite sides of the refrigerant receptacle 118 90 and these may be again sub-divided to produce additional and separate compartments. In Figure 8 there is shown the compartments 139, 140 and 141 and 142. Below the 100 compartments 141 and 142 are shown parts of the lower compartments 143 and 144. It will be understood that there are similar compartments below the compartments 139 and 140. It will also be understood that 105 the same form of construction may be used for other compartments above these shown in the figure referred to.

The refrigerant receptacle 119 is also provided with the angle iron braces 145 and 110 146.

115 It will be seen that the cooling mixture may be introduced into the refrigerant receptacles 116, 117 and 118 through the openings 120, 121 and 122 without necessitating the removal of the receptacle 119 when any or all of them need filling.

In this modified structure the vehicle has running boards on opposite sides of the body. The running board 147 is provided 120 with the hinged extension 148 and the running board 149 is provided with the hinged extension 150. These provide wider portions for the driver to stand upon when removing the cans from within the cooling 125 chambers. It is understood that these running boards may be provided with proper abutments to assist in maintaining hinged extensions in the position shown in Figure 8.

Having thus described the invention, what I claim and desire to secure by Letters Patent is:

1. In a vehicle, the combination of a body, 5 a cooling chamber arranged within the body, a plurality of separate receptacles for receiving a cooling medium, said receptacles providing the walls of said cooling chamber, a partition arranged within the cooling 10 chamber, said partition being connected to the receptacles and providing a support therefor.
2. In a vehicle, the combination of a body, 15 a cooling chamber arranged within the body, a plurality of separate receptacles for receiving a cooling medium, said receptacles providing the walls of said cooling chamber, a partition arranged within the cooling 20 chamber, said partition being connected to the receptacles and providing a support therefor, a transverse partition, said transverse partition being connected to the first mentioned partition and assisting to support the same.
- 25 3. In a vehicle, the combination of a body, a cooling chamber arranged within the body, a plurality of separate receptacles for receiving a cooling medium, said receptacles providing the top and side walls of said 30 cooling chamber, a partition arranged within the cooling chamber, said partitions being separably connected to the receptacles and providing a support therefor.
- 35 4. In a vehicle, the combination of a body, a cooling chamber arranged within the body, a plurality of separate receptacles for receiving a cooling medium, said receptacles providing the top and side walls of said 40 cooling chamber, a partition arranged within the cooling chamber, said partition being separably connected to the receptacles and providing a support therefor, a transverse partition, said transverse partition being connected to the first mentioned partition and 45 assisting to support the same.
5. In a vehicle, the combination of a body, a cooling chamber arranged within the body, a plurality of separate receptacles for receiving a cooling medium, said receptacles 50 providing the walls of said cooling chamber, a plurality of partitions arranged within the cooling chamber, said partitions being removably connected to said receptacles, transverse partitions arranged to support 55 the first mentioned partitions, said partitions dividing the cooling chamber into a plurality of compartments, and a container removably arranged in one of said compartments.
- 60 6. In a vehicle, the combination of a body, a cooling chamber arranged within the body, a plurality of separate receptacles for receiving a cooling medium, said receptacles providing the walls of said cooling chamber, 65 insulated walls surrounding the receptacles,
- a plurality of partitions being removably connected to said receptacles, transverse partitions arranged to support the first mentioned partitions, said partitions dividing the cooling chamber into a plurality of compartments, and a container removably arranged in one of said compartments. 70
7. In a vehicle, the combination of a body, a cooling chamber arranged within the body, a plurality of separate receptacles for receiving a cooling medium, said receptacles providing the walls of said cooling chamber, one of said receptacles having an extension which telescopes into the other of said receptacles. 75
8. In a vehicle, the combination of a body, a chamber provided within said body, a cooling chamber arranged within the first mentioned chamber, a plurality of receptacles for receiving a cooling medium, said receptacles providing the walls of said cooling chamber, one of said receptacles having means cooperating with the four walls of said first mentioned chamber for supporting said receptacle. 85
9. In a vehicle, the combination of a body, a chamber arranged within said body and a cooling chamber arranged within the first mentioned chamber, a plurality of receptacles for receiving a cooling medium, said receptacles providing the side walls and top of the cooling chamber, the receptacle providing the top of the cooling chamber having three apertures for the passage of cooling medium into the three receptacles respectively providing the side walls of the cooling chamber, said top having means cooperating with the four walls of said first mentioned chamber for supporting said receptacle, said top being removable from the 90 receptacles forming the side walls to permit access thereto. 100
10. In a vehicle, the combination of a body, a chamber arranged within said body and a cooling chamber arranged within the first mentioned chamber, a plurality of receptacles for receiving a cooling medium, said receptacles providing three of the side walls and top of the cooling chamber, the receptacles providing the top of the cooling chamber having three apertures for the passage of cooling medium into the three receptacles respectively providing the side walls of the cooling chamber, said top having means cooperating with the four walls of said first mentioned chamber for supporting said receptacle, said top being removable from the receptacles forming the three side walls to permit access thereto. 110
11. In a vehicle body, the combination of a chamber, a cooling chamber arranged with- 115
12. In a vehicle body, the combination of a chamber, a cooling chamber arranged with- 120
13. In a vehicle body, the combination of a chamber, a cooling chamber arranged with- 125
14. In a vehicle body, the combination of a chamber, a cooling chamber arranged with- 130

in the first mentioned chamber, receptacles for receiving a cooling medium arranged within the first mentioned chamber and providing the top and side walls of the cooling chamber, one of said receptacles being arranged transversely to the other receptacles and providing a partition for the cooling chamber, said receptacle providing the top wall having means whereby the refrigerant may be supplied to said side and transversely arranged receptacles.

12. In a vehicle body, the combination of a chamber, a cooling chamber arranged within the first mentioned chamber, receptacles for receiving a cooling medium removably arranged within the first mentioned chamber and providing the top and side walls of the cooling chamber, one of said receptacles being arranged transversely to the other receptacles and providing a partition for the cooling chamber, said receptacle providing the top wall having means whereby the refrigerant may be supplied to said side and transversely arranged receptacles.

13. In a vehicle body, the combination of a chamber, a cooling chamber arranged within the first mentioned chamber, a plurality of receptacles for receiving a cooling medium arranged within the first mentioned chamber, said receptacles providing the walls of the cooling chamber, one of said receptacles being arranged transversely to the other receptacles and dividing the cooling chamber, a receptacle providing the top wall of the cooling chamber, said last mentioned receptacle and the before mentioned receptacles having cooperating means whereby the cooling medium introduced into the uppermost receptacle may be passed therefrom into the first mentioned receptacles.

14. In a vehicle body, the combination of a chamber, a cooling chamber arranged within the first mentioned chamber, a plurality of receptacles for receiving a cooling medium arranged within the first mentioned chamber and providing the walls of the cooling chamber, each of said receptacles being

provided with a plurality of partitions forming a plurality of refrigerant compartments in said receptacles, a receptacle providing the top wall of the cooling chamber, said last mentioned receptacle and the receptacles providing the side walls of the cooling chamber having cooperating means whereby the cooling medium introduced into the uppermost receptacle may be passed therefrom into the first mentioned receptacles, the first mentioned chamber having an opening and a closure for the opening, said opening permitting the introduction of the cooling medium into said receptacle providing the top wall of the cooling chamber and into said compartments in said receptacles providing the side walls of said cooling chamber.

15. In a vehicle body, the combination of a cooling chamber including a plurality of receptacles for receiving a cooling medium, one of said receptacles being arranged transversely to the other receptacles and providing the walls of the cooling chamber and dividing the cooling chamber, the receptacle providing the top wall of the cooling chamber and the receptacles providing the side walls of the cooling chamber having cooperating means whereby the cooling medium introduced into the uppermost receptacle may be passed therefrom into the first mentioned receptacles.

16. In a vehicle body, the combination of a cooling chamber, a plurality of receptacles for receiving a cooling medium, and providing the side walls of the cooling chamber, each of said receptacles being provided with a partition, a receptacle providing the top wall of the cooling chamber, said last mentioned receptacle and the before mentioned receptacles having telescopic means whereby the cooling medium introduced into the uppermost receptacle may be passed therefrom into the first mentioned receptacles.

In witness whereof, I hereunto subscribe my name this 9th day of May, A. D., 1921.

LOUIS B. OLIN.
